GRIP DEVICE FOR EARTH BORING APPARATUS

James E. C. Currens, San Anselmo, Calif.

Application February 24, 1931. Serial No. 517,935

6 Claims. (Cl. 255—20)

This invention relates to earth boring apparatus of the horizontal type, and more particularly to an improved grip device for engaging the boring bar when it is desired to unscrew the sections 5 thereof.

More specifically, the present invention constitutes an improvement over the grip device shown and described in application Serial No. 469,906, filed July 22, 1930 by Alfred E. Englebright, Fred- 10 erick J. Foret and myself. In said prior applica- 15 tion is shown earth boring apparatus comprising a track and a carriage movable along such track, on which carriage is mounted the boring bar and a motor for driving the same. At the front end 15 of the track, there is provided a grip device through which, when released, the boring bar can freely move, but which may be actuated to grip and hold the boring bar against rotation, so that the sections thereof may be disconnected by re- 20 versing the direction of rotation of the motor.

In said application, there is also disclosed ream- 25 ing devices adapted to be inserted at any desired point between boring bar sections, and serving to enlarge the hole bored by the auger. With the construction of grip device shown in said prior application, it was impossible to assemble these 30 reaming sections into the boring bar at the most convenient point to insert them, namely, between the grip device and the carriage, because these 35 reamers, being of relatively large diameter, would not pass through the grip device. Consequently, it was necessary to insert the reamer sections at a point ahead of the machine and beyond the track. This not only required the provision of additional 40 space to make possible the necessary manipulations, but also necessitated the use of hand wrenches to hold the boring bar in order that two adjacent sections might be disconnected for the purpose of inserting a reamer section.

45 The object of the present invention is to overcome these objections and disadvantages by providing an improved grip device which may be detachably clamped or secured to the track and which, furthermore, is split, so that it may be dis- 50 engaged from the boring bar. In this way, when it is desired to insert a reamer section, the grip device may first be employed to hold the boring bar so that two adjacent sections may be un- 55 screwed, and so that a reamer section may be in- serted at a point between the carriage and grip device, and subsequently, after such reamer sec- 60 tion has been inserted, the grip device may be bodily removed from the track and from engage- 65 ment with the boring bar, so as to permit the free 70 passage of the reamer section as the carriage moves forwardly.

In order that the invention may be readily understood, reference is had to the accompanying drawings forming part of this specification and 60 in which:

Fig. 1 is a front elevation of the end of the track of an earth boring machine, showing my improved grip device mounted thereon;

Fig. 2 is a plan view of the main section or body of said grip device;

Fig. 3 is a side elevation thereof;

Fig. 4 is a plan view of the auxiliary or tilting section of the grip device;

Fig. 5 is a side elevation thereof;

Fig. 6 is a side elevation of a latch device which I employ to hold the two sections of the grip de- 70 vice together; and

Fig. 7 is a fragmentary plan view on a reduced 75 scale showing the general arrangement of earth boring apparatus in connection with which the present invention is employed.

Referring to the drawings in detail, I have shown a track similar to that disclosed in the said prior application. This track comprises a pair of spaced parallel rails 1 shown as in the form of channel beams having inwardly directed flanges. As in said prior application, the rails are secured in position by means of cross ties 2 and braces 3.

As shown in Fig. 7, the complete apparatus 80 comprises a boring bar 30 attached to the forward end of a power shaft by means of a grip device 36, such power shaft extending through a water box or hydraulic head 31, for supplying water to the interior of the boring bar. The power shaft is driven by a motor 34 which, together with the hydraulic head 31, is mounted upon a suitable carriage 32, 33 having wheels 35 adapted to travel on the rails 1. A rack 1^a is preferably as- 85 sociated with these rails by means of which the carriage may be propelled, in a manner illus- 90 trated, for example, in my copending application Serial No. 514,847, filed February 10, 1931.

95 My improved grip device comprises a main body or skeleton frame 4 having formed in its upper portion a substantially semi-circular seat 5 of a size adapted to receive the boring bar.

An upper or auxiliary section 7 is provided and has formed in its lower face a similar semi-circular seat 6, these two semi-circular portions serving, when the parts are assembled, to form a circular opening, as shown in Figure 1, through which opening the boring bar loosely passes and in which it may turn, as in a bearing.

100 The upper auxiliary section or jaw 7 is pivotal- 105 ly connected at 8 to the lower or main section 4, such pivotal connection being effected by means of spaced eyes 7^a formed at the end of the section 7, and a similar eye 9 formed on the main section 4 and adapted to be received between the eyes 7^a, a pivot pin passing through the aligned eyes. 110 Adjacent the eye 9 is an abutment 10 which serves to limit the pivotal movement of the sec- 115 tion or jaw 7 when it is swung to open position, as shown in dotted lines in Fig. 1.

120

The swinging section or jaw 7 is provided at its middle with a transverse opening 11 adapted to receive a pivot pin 12, and the jaw 7 itself is formed hollow adjacent such opening so as to provide a recess or chamber 7^b (see Fig. 4). Housed within this recess and mounted to turn upon the pin 12 is a cam shaped toothed dog 13 having an operating handle 14 by means of which it may be swung, this device being similar to that shown in said prior application. In order to strengthen and reinforce this cam dog, a U-shaped bracket 15 embraces the same and the jaw 7 and is also pivotally mounted at its ends upon the pin 12, as shown in Fig. 1.

15 In order to latch the main and auxiliary sections of the grip device together, I form on the main section or frame 4 adjacent the seat 5 a hook 16, as shown in Fig. 3, and to cooperate with this hook I provide a swinging bail 17 pivotally mounted on a pin 18 extending transversely through and arranged eccentrically of a cylindrical member 19 to which an operating handle 20 is rigidly secured, as clearly shown in Fig. 6.

At the free end of the auxiliary section or jaw 25 7, I provide a pair of spaced slotted openings 21 and an arcuate seat 22 adjacent and between the same, as shown in Figs. 4 and 5.

It will now be understood that the cylindrical member 19 works against the arcuate seat 22, 30 while the pin 18 works in the slots 21, and that by reason of the eccentric mounting of this pin in the member 19, the bail 17 can first be swung into position under the hook 16 and then drawn snugly up against the hook by rotating the handle 35 20, thereby securely locking the two sections of the grip device together.

Referring to Figs. 1 and 3, it will be seen that the main section or frame 4 of the grip device bridges the rails 1, and this frame is preferably 40 formed at its ends with seats 23 adapted to fit over the inturned flanges of the rails.

The frame 4 is further provided at its lower side with a pair of spaced studs 24 which project downwardly from the under surface thereof, as 45 best shown in Fig. 3, and these studs fit easily into a pair of openings or sockets formed in a yoke member 25. This yoke member is, as shown in Fig. 1, substantially coextensive with the frame 4 of the grip device and is arranged to engage 50 underneath the rail flanges.

Extending vertically and centrally through the lower portion of the frame 4 is an opening 26, as shown in dotted lines in Fig. 2, and adapted to register with this opening is a similar but screw 55 threaded opening 28 formed in the yoke 25. A screw 27, having at its upper end a hand wheel 29 or the like, passes freely down through the opening 26 and engages the threads in the opening 28. Thus, when the hand wheel 29 is turned, the yoke 60 25 is drawn firmly toward the frame 4, being held in position by the studs 24, and thus clamps the rail flanges between itself and said frame.

From the foregoing, it will be seen that by virtue of my improved construction, the grip device 65 can be secured in any desired position along the track and may be firmly clamped so as to be held in such position by friction only, without the use of any bolts or other fastening devices. It will similarly be seen that by a mere loosening of 70 the screw 27 the yoke 25 can be released and the entire grip device bodily removed from the track.

It will further be obvious that when it is desired to remove the grip device, as described, the bail 17 will be disengaged from the hook 16 and

the auxiliary section or jaw 7 swung about its pivot 8 into dotted line position so as to clear the boring bar. When the jaw is thus opened, the grip device can, of course, be moved laterally out of engagement with such bar, and thus 80 entirely taken off the machine.

In conclusion, it will now be appreciated that when it is desired to introduce a reamer section between two boring bar sections, the lever 14 is 85 swung to one side so as to cause the cam dog 13 to engage and grip the bar, and the motor is then reversed so as to unscrew the desired coupling. The reamer section is then inserted in the usual manner and then the entire grip device is disengaged from the boring bar and removed from the track, so as to afford free passage to the reamer section as the carriage and boring bar travel forward. In this way, the use of hand wrenches, with their attendant dangers to the workmen, is avoided and, furthermore, no 90 extra space in advance of the machine is required.

What I claim is:

1. Earth boring apparatus comprising, in combination, a track, a carriage movable therealong, 100 and a boring bar mounted on the carriage, a grip device for engaging the boring bar, and means whereby said grip device may be detachably secured to said track.

2. Earth boring apparatus comprising, in combination, a pair of track rails, a carriage movable therealong, and a boring bar mounted on the carriage, a grip device for engaging the boring bar, and means whereby said grip device may be detachably clamped to said track rails and 105 held in position thereon solely by friction.

3. Earth boring apparatus comprising, in combination, a pair of track rails having flanges, a carriage movable therealong, and a boring bar mounted on the carriage, a grip device for engaging the boring bar, and means whereby said grip device may be detachably clamped to the 115 flanges of said track rails.

4. In earth boring apparatus of the type comprising a track, a carriage movable therealong, 120 and a boring bar mounted on the carriage, the combination with a track comprising a pair of spaced parallel rails having inwardly projecting flanges, of a grip device for engaging the boring bar, said grip device having a frame bridging said rails, and a yoke member substantially co-extensive with said frame, and means for clamping said flanges between said frame and yoke member so as to frictionally hold said grip device in any desired position on said track. 125

5. Earth boring apparatus comprising, in combination, a track, a carriage movable therealong, 130 and a boring bar mounted on the carriage, a grip device for engaging the boring bar, said grip device comprising a pair of separable sections whereby it may be disengaged laterally from said bar, and means for detachably securing said grip device to said track, so that it may be removed when desired.

6. Earth boring apparatus comprising, in combination, a track, a carriage movable therealong, 140 and a boring bar mounted on the carriage, a grip device for engaging the boring bar, said grip device comprising a pair of hingedly connected separable sections, whereby it may be removed laterally from said boring bar, and means for rigidly and detachably securing said grip device 145 to said track.

JAMES E. C. CURRENS.
